UNITED STATES PATENT OFFICE.

GOTTLIEB KLENK, OF DEFIANCE, OHIO, ASSIGNOR TO THE DEFIANCE PRESSED STEEL COMPANY, A CORPORATION OF OHIO.

SHEET-METAL BOX.

1,139,537.

Specification of Letters Patent. Patented May 18, 1915.

Application filed April 10, 1911, Serial No. 620,068. Renewed April 3, 1915. Serial No. 19,035.

To all whom it may concern:

Be it known that I, GOTTLIEB KLENK, a citizen of the United States, residing at Defiance, in the county of Defiance and State 5 of Ohio, have invented certain new and useful Improvements in Sheet-Metal Boxes, of which the following is a specification, reference being had therein to the accompanying drawing.

- 10 This invention relates to improvements in sheet metal boxes of the class used for storing and transporting bottles containing liquids; it pertaining more particularly to boxes of this sort which have open bottoms 15 furnished with wire supports for the bottles, and also having longitudinal and transverse sheet metal partitions, whereby the interior of the box is divided up into bottle compartments.
- 20 Figure 1 is a perspective view of the box as a whole. Fig. 2 is a bottom plan view. Fig. 3 is a longitudinal cross section taken along the line 3—3 of Fig. 2. Fig. 4 is a transverse cross section taken along the line 25 4—4 of Fig. 2. Fig. 5 is an enlarged fragmentary cross section similar to Fig. 3. Fig. 6 is an enlarged fragmentary cross section taken along the line 6—6 of Fig. 2.

The box is made of sections of sheet metal 30 suitably secured together and properly reinforced.

2, 2 indicate the side walls, and 3, 3 the end walls, each formed of a section of sheet metal which in general formation is rectangular. The side sections and the end sections are crimped together to form the vertical corner flanges 4. The top of the box is preferably provided with a strong flat binding and reinforcing metal bar 5. 35 Around this the upper edge parts of the side sections 2 and the end sections 3 are crimped, preferably by having formed therein, respectively, flat beads, each having the outward turned horizontal flange part 5^a, the edge part 5^b, the top horizontal flange part 5^c, and the outwardly turned lip 5^d which lies under the inner edge of the flat band 5.

To further reinforce the upper portion of the box, and add to the strength given 50 by the flat band 5, I employ metallic bars 6 which are riveted to the side wall sections 2. These extend from one of the corner crimps at 4 to the opposite one and are placed as snugly as possible under the outwardly overhanging part of the band strip 5, so that any

vertical distorting force applied to the top band shall be immediately met and resisted by the bars or bands 6. To increase this resisting efficiency against downward bending of this upper reinforcement, I prefer 60 to crimp the bars or bands 6, as shown at 6^a. The crimps should not extend beyond the outer edge of the overhanging flange part at 5^b, lest projections should appear which will be dangerous in the handling, shoving, 65 or throwing of the boxes. The crimps or offsets at 6^a serve as pillars or abutments to prevent the parts at 5, 5^b from being bent or distorted downward.

The side wall sections and the end wall sections, at their lower edges, are bent outward and then inward to form the flange 7. Horizontal sheet metal strips 8, 9 are provided and the outer edges of these are folded or crimped with the metal of flange 7, as 70 shown in the drawing, whereby the flange 7 is reinforced and the strips 8 and 9 are held securely in place at the bottom of the box. At 10 there is an additional bend given to each side wall and each end wall section so 75 as to bring the metal of these sheets snugly down to engage the top of the bent portion of the strips 8 and 9. There are two of the strips 8, one for each end. Of the strips 9 there are two, one for each of the long sides. 80 The strips 8 are beaded at their inner edges to form a downwardly extending projection 11. The strips 9 are each formed with two relatively long beads 11^a, and an intermediate shorter bead 11^b.

12 and 12^a are heavy wire rectangles. Each is secured in place by one of the beads 11 and two of the transversely opposite beads 11^a formed on the strips 8 and 9. Supplemental to these beaded strips, 8 at 90 the ends, and 9 at the sides, there are metal strips 8^a and 9^a. Those at 9^a are at their outer edges crimped in with the parts at the flanges 7. The opposite edges of these strips 9^a are turned downward and upward above, the strips 9, a strong interior flange being thus provided at each side of the bottom part of the box. The end strips 8^a are similarly crimped at their outer edges with the parts of the flange 7. These have their 95 inner edges also turned backward or outward and clamped firmly with the aforesaid strips 8 and immediately above them. These strips 8^a have beads at 8^b for the purpose to be described.

110

The two wire rectangles 12 and 12^a and their beads project well below the lowermost parts of the other elements of the box above referred to and form a strong rest 5 upon which the box and its contents can be safely supported when standing on a flat surface. The innermost legs or cross bars of the wire rectangles 12 and 12^a are firmly bound together by means of a sheet metal 10 cross strip 13 which is beaded at its edges, as shown at 13^a, the beads firmly inclosing the inner legs or bars 12^b of the wire rectangles. The bottom surface of this binding sheet, band, or bar 13 is in the horizontal 15 plane of the bottom edges of the beads 11 and 11^a, and this assists in giving a firm binding for the base parts of the box and a strong support for the box, as a whole, and its contents.

20 It will be seen that the rectangular base projection which extends downwardly (and formed of the two wire rectangles 12 and 12^a, together with the beads 11 and 11^a and the binding and connecting strip 13) has its 25 outermost lines so arranged that while they are parallel to the bottom edges of the end sections and the side sections of the box, they lie at a distance inside of the edge lines. This provides for a strong stacking "rest" 30 outside of the rectangular base, this rest being composed of the crimped or bent parts of the wall sections and the crimped strips 8, 9, 8^a and 9^a. One box can be placed directly upon the top of another, the bottom 35 "rest" of one bearing downward upon the top bracing flange at 5° of the one below and the base rectangle of the upper one fitting inside the inner edges of the top of the box below, so that horizontal displacement 40 of any box in the stack is prevented.

In addition to the parts above described, use is made of a series of interior walls or partitions 16. These lie parallel to the end walls and are so arranged as to divide transversely the interior of the box into substantially equal divisions. Each of these is secured to the side walls of the box by flanges 45 16^a and rivets 16^b. At the upper edges they are provided with small beads 16^c which surround bracing wires 16^d. At their lower edges they are formed with beads 16^e.

Longitudinally of the box there are narrower vertically arranged partition walls 17. These intersect the partitions 16 in such way 55 as to furnish a series of bottle compartments substantially square in plan outline. They do not extend downward to the bottom of the partitions 16, such a width not being required.

60 18, 18 are bottle supporting rods preferably made of lengths of wire. They are so arranged as to present two parallel bars under the central part of each longitudinal row of bottle compartments. The two bars 65 of each pair may be formed of one piece of

wire bent at the central part of the total length to give a short cross connecting section at right angles to the two longitudinal parts and shaped at their ends to have two L bends. The central connecting part and the two L bends are placed in the beads 8^b in the end flange strips 8^a above described. The rods 18, 18 extend through apertures in the interior partitions 16 near the lower edges of the latter.

70 It will be observed that the beads 16^c at the bottoms of the partitions 16 are arranged on lines so high relatively to the bottom edges of the base rectangle 12 and 12^a that the partitions are relieved of all 80 strain.

75 Heretofore I have constructed boxes of this sort in the manner shown in my Patent No. 912,273, issued February 9, 1909. These earlier boxes had the longitudinal partitions 85 extended down far enough to bring their beads and bead wires substantially flush, or in the same horizontal planes, with the lowermost surfaces of the bottom parts of the box. This was done in order to have 90 the partitions of the bottle compartments take much of the strain experienced by the lowermost parts, and particularly designed to have the lower edges of the partitions contact with and ride upon the rollers in 95 the gravity roller conveyors commonly used in breweries and similar places where the bottles are filled and the cases are charged. But experience with the boxes shown in the 100 aforesaid Patent No. 912,273 has shown that 100 the partitions (either the shorter transverse partitions or the longer longitudinal ones) when subjected to such strains, arising from assisting in supporting the box, are speedily twisted and distorted. This carrying of 105 the partition walls down to the lower horizontal plane of the box was largely necessitated because there was present only one base rectangle at the bottom of the box, that is, a single rectangular wire seated in beads 110 at the ends of the box and at the sides.

115 In the present construction I divide the bottom area of the box into two approximately equal parts by the base rectangles 12 and 12^a, and by combining with these the binding sheet or bar 13 I furnish a supporting device which takes the entire thrust and strain in such way that the partitions 16 and 17 are relieved of all the twisting and distorting action, as their lower edges are removed from contact with the supporting bodies below the box.

120 What I claim is:—

1. In a sheet metal box of the class described, comprising side and end sections 125 crimped at their lower edges to form a horizontal flange around the bottom of the box, a rectangular wire stacking base projecting downward below the flange along lines within the periphery thereof, beaded sheet metal 130

strips secured to the side and end sections and serving to hold the wire base in place, a series of vertical transverse partitions provided at their lower edges with beads located 5 above the bottom plane of the said stacking base, a series of vertical longitudinal partitions, the two series of partitions serving to divide the box into bottle compartments, and a series of longitudinal bottle support- 10 ing rods having their end parts rigidly secured to the end sections of the box, the intermediate parts of the rods extending through the transverse partitions and being supported thereby. 15 2. A sheet metal box of the class de- scribed, comprising side and end sections crimped at their lower edges to form a horizontal flange around the bottom of the box, a rectangular stacking base formed of two 20 adjacent wire rectangles, the base projecting downward below the flange along lines with- in the periphery thereof, beaded sheet metal

strips secured to the side and end sections and engaging the outer sides of the wire rectangles to hold them in place, a binding strip for holding together the adjacent inner sides of the wire rectangles, a series of vertical transverse partitions terminating at their lower edges in beads above the bottom plane of the base, a series of vertical longi- 25 30 35

tudinal partitions, the two series of partitions serving to divide the box into bottle compartments, and a series of longitudinal bottle supporting rods having their end parts rigidly secured to the end sections of the box, the intermediate parts of the rods extending through the transverse partitions and being supported thereby.

In testimony whereof I affix my signature, in presence of two witnesses.
